BRAKE BEAM SUPPORT

Donald S. Barrows, Rochester, N. Y., assignor to
 The Symington-Gould Corporation, Rochester,
 N. Y., a corporation of Maryland

Application January 15, 1945, Serial No. 572,894

17 Claims. (Cl. 188—190)

1

The invention pertains to a brake beam support and more particularly to a compensating type thereof.

A broad object of the invention is the provision of a member comprising a support for brake beams and being movably carried by a side frame, the latter of which is arranged to travel vertically relative to associated journal boxes.

Another object of the invention is the provision of a member forming a support for brake beams and being carried by a side frame with means connecting the member to journal boxes in such a manner as to maintain the member in a fixed position relative to the journal boxes while the side frame is arranged to move vertically relative to the journal boxes.

The above, as well as numerous other objects will become apparent from the accompanying drawings, considered in conjunction with the succeeding detailed description. Reference is now made generally to the drawings, wherein:

Figure 1 is a side elevational view of a portion of a railway truck embodying a form of the present invention.

Figure 2 is a plan view of the structure illustrated in Figure 1.

Figure 3 is a vertical cross sectional view taken along the lines 3—3 of Figure 1, looking in the direction of the arrows.

Figure 4 is a perspective view of a member forming guideways for brake beams.

Referring now in detail to the drawings, wherein, throughout the several views, like reference characters indicate like parts, the numeral 1 is employed to designate, in a somewhat general manner, a railway car truck. The railway truck comprises a pair of side frames 2, only a portion of one of which is illustrated in the drawings because it is commonly known that a railway truck comprises two side frames spaced transversely of the truck and extending longitudinally thereof. The side frames are tied together intermediate their ends by a load-carrying member or transversely extending bolster 3 having an end portion 4 disposed in a window 5 of the side frame to be there interlocked with the side frame and to transmit the load of a car body (not shown) to the frames. The railway truck with which the present invention is particularly adaptable is the type thereof wherein the side frames are resiliently supported and, accordingly, the vertical disposition of an individual side frame is changing continually in running service and also during the loading and unloading of the car body. As illustrative of the type of railway car truck here-

inabove discussed, there is shown a journal box 6 positioned adjacent each end of a side frame and forming a housing for bearings (not shown) of any type and which afford a free running movement of a wheel and axle assembly 7. Each journal box disposed between spaced jaws 8 of the side frame adjacent an end thereof may have outstanding therefrom wings or shelves 9 with the jaws forming containers or housings for resilient means 9a the latter of which are interposed between the side frame and journal box shelves to thereby present a flexible or resilient support for the side frame. This described structure of journal box mounting may be as illustrated, described and claimed in United States Patent No. 2,297,863, granted October 6, 1942, to D. S. Barrows et al. In this type of railway truck, because of the presence of the flexible or resilient support, and considered together with the fact that the vertical disposition of the axis of a wheel and axle assembly remains constant with respect to a supporting rail throughout all service truck movements, the vertical relationship between the side frame and wheel and axle assembly is subjected to variation.

The most commonly employed means to impede the progress of a railway car or retain a railway car in a predetermined position is a component of the railway truck, namely a brake beam which is designated, throughout the several views of the drawings, by the reference character 10. The brake beam extends horizontally or transversely of the truck and has associated therewith, adjacent its extremities, brake shoe heads and replaceable brake shoes 11 arranged to contact wheels of a wheel and axle assembly.

For reasons that are apparent to those skilled in the art and need not be herein enumerated, an ideal condition is attained when the brake beam, though supported by a side frame, is maintained at a predetermined elevation so that, irrespective of any vertical variation between the side frame and wheel and axle assembly, the brake beam will at all times travel along a fixed and definite path during an application or release action of the brakes. Toward the attainment of the above ideal condition, there is provided a brake beam carrier or support 12 desirably of cast form but, as will be appreciated, may be formed as a fabricated component. The instant structure is concerned primarily with the type of brake beam having an extension 13 of elongated cross sectional configuration and which projects outwardly of the truck from a related 55 brake head in contrast to the type thereof em-

ploying a pivotal or swing hanger suspended from a jaw formed integral with the side frame and interlocked with the brake head. The brake beam support extends longitudinally of the truck between wheel and axle assemblies and below or adjacent to the inner edge of the side frame. Preferably the brake beam support comprises an intermediate bridge or spacer portion 14 having an upper horizontal top web 15 with depending, transversely spaced, vertical webs 16 to thus present an inverted U-shape in cross section. It will be clearly understood, however, that the cross sectional configuration of the intermediate portion may be of any rigid, desired or optional design, just so long as it is capable of performing the function for which it is intended, herein-after made apparent. Formed at each end of the top web is a guideway 17 defined in part by a bottom or lower wall 18, the latter of which in effect, forms a continuation of the top web. Spaced a predetermined distance above each lower wall and desirably parallel therewith, is a top or upper wall 19 defining the upper limits of the related guideway and having one end thereof connected integrally to the associated end of the bottom wall through the medium of an end wall 20. An inner web 16a of the intermediate portion webs merges into the bottom walls in underlying relation thereto while the outer web 16b of these webs extends through the plane of the bottom walls to merge with the top and end walls and thus not only form rigidifying tie means but also present side walls 21 of the guideways closing the outer limits thereof. The brake beam support is thus made as an integral, rigid member with brake beam guideways at each end thereof in the proximity of wheels of the wheel and axle assemblies with the guideways opening transversely or inwardly of the truck for the accommodation of the brake beam extensions 13 and also opening toward one another so that the brake beam may, if desired, be introduced into the guideways through these latter mentioned openings. Associated with each guideway is a substantially channel-shaped wear plate 22 secured to the top and bottom walls by means of the illustrated welds or any other desired means.

From long and established practice, brake beams are most usually disposed below a horizontal plane bisecting the axis of the wheel and axle assembly and arranged so as to move along a path which, if extended, bisects the axis of the wheel and axle assembly so that the included angle between the extended path and a horizontal plane above mentioned will approximate 12 degrees. Accordingly, each guideway is inclined or disposed upwardly and outwardly or longitudinally of the truck so that the brake beam will travel, during application and release of the brakes, along a path which, if projected, will intersect the axis of the wheel and axle assembly.

As previously implied, means has been incorporated in the truck to maintain the guideways in a fixed position and, as exemplary of such a means, there is provided adjacent each side of the bolster opening and near the lower limits thereof a lever means 23. Each lever means desirably comprises an inner arm 24 positioned inwardly of the truck from a related side frame and inclined downwardly and toward an associated end of the side frame away from the bolster opening. The free end of each inner arm is formed as an apertured boss 25 which fits between apertured hinging lugs 26, the latter upstanding from a top wall of a guideway. A

pin 27 locked in place by a cotter 27a extends through the hinging lugs and boss to pivotally connect each inner arm to an extremity of the guideway member. Because, as hereinafter pointed out in more detail, the inner arm is also pivotally mounted, an aperture of one of the bosses is desirably elongated as at 28 in order to eliminate a binding action during service movements of the side frame. Forming an intermediate portion of each lever means is a shaft 29 projecting outwardly or transversely of the truck from one end of an inner arm as an integral part thereof. Each shaft is desirably of circular cross section to be journaled in and carried by the side frame so as to pivot relative thereto and terminates beyond the side frame as a squared extension 30. Mounted upon each squared shaft extension is an outer arm 31 having one or a lower extremity 32 apertured to neatly accommodate the related shaft extremity where it is retained in position by means of a removable element or cutter 33. Each outer arm desirably extends from the shaft in an upwardly direction and sloping toward a related end of the side frame. An upper extremity of each outer arm presents a jaw 34 opening upwardly of the truck.

Depending from a jaw 8 of the side frame, particularly an inner jaw between each journal box and the bolster opening, is a pair of hinging ears 34a forming desirably downward integral continuations of the jaw to be spaced apart transversely of the truck. This particular disposition of the hinging ears will not interfere with the clear opening into the jaws for the introduction of the journal box shelves therein. Associated with each pair of hinging ears is a rotatable pivot or crank means 35 comprising an intermediate U-shaped clamp which terminates in embossments or bearings 36. The clamp of each crank straddles the hinging ears in lower spaced relation to the side frame proper so that the bearings overlie in intimate contact the hinging ears. A pivot pin 37 extends through aligned openings in the related embossments and hinging ears to pivotally secure the crank to the side frame. Cotters 38 or any desirable removable means bisect the pivot pin beyond the limits of the embossments to retain the crank assembled with the pivot pin and side frame. Each embossment, positioned outwardly of the truck, is provided with an outer arm or leg 39 formed integrally with the clamp so as to move therewith and is spaced a slight distance outwardly from the side frame. Each outer leg extends in an upward inclined direction toward a related end of the side frame to be disposed at substantially the same inclination as an associated outer arm 31. Like the outer arms, each outer leg has an upper extremity thereof formed as a jaw 40. Pivotally connecting or joining related leg and arm jaws through the medium of pins 41 is a connecting link or rod 42 which reflects a motion of the crank of the lever means. That is to say, any pivotal movement of the rotatable means will be reflected immediately in a corresponding movement of the lever means.

Each clamp has a lower or side arm or leg 44 projecting toward a journal box from the center of the clamp and desirably but not necessarily disposed in the vertical longitudinal plane of the side frame characterized in Figure 2 by the diagrammatic line A—A. A free end of a lower leg is cylindrical or more particularly barrel-shaped as at 45 and underlies the journal box proper so

that a plane passing vertically through the axis of the cylindrical end coincides with a transverse vertical plane bisecting the axis of the wheel and axle assembly. This relationship is preferred because of the tendency, due to slight clearances between the journal box and side frame, for the journal box to move horizontally in several directions relative to the side frame and, accordingly,

It is believed that a more accurate vertical movement of the side frame will be reflected by this particular lower leg end and journal box relationship. It is quite possible that a true and accurate relative vertical movement between the journal box and side frame will be reflected in the crank and lever means if the cylindrical end is associated with any portion of the journal box and this latter suggested relationship is to be considered within the scope of the appended claims.

In order that the barrel leg end may, throughout all service movements of the truck components, be in substantially intimate contact with the journal box, there is provided a clip or U-shaped strap 46 depending from a floor of a journal box to present a housing 47 or enclosure for a lower leg extremity. A bottom wall of a journal box has secured thereto a wear plate 48 while a spring or any resilient means 49 underlies the lower leg extremity and is interlocked with a strap to maintain at all times the lower leg extremity in intimate contact with a wear plate. The relation of a leg cylindrical end with a wear plate and spring presents a pivotal or movable or flexible connection between the journal box and rotatable means.

A journal box may be so associated as to move transversely of the truck relative to the side frame and, to meet such a contingency, sufficient clearance is provided between extremities 50 of a cylindrical end and a clip to allow a free transverse movement of the journal box without any interference by a crank side leg.

The particular inclination and effective length of the crank lower arm is substantially the same or equal to the downward and outward inclination and effective length of a lever means inner arm. Accordingly, and because of the similarity between a crank outer leg 39 and a lever outer arm, any vertical movement of the side frame relative to a journal box will result in a corresponding or equal rotary motion of a crank and lever to maintain the brake beam guide member in a fixed position relative to a wheel and axle assembly or journal box. Such vertical relative movement will, in other words, cause a corresponding or identical relative movement between the brake beam guide member and side frame to thus compensate for any or all vertical movements between the journal box and side frame.

From the above it will be noted that various changes and alterations can be made to the illustrated and described construction without departing from within the spirit of the invention and scope of the appended claims.

I claim:

1. In a railway car truck wherein a side frame and journal boxes are arranged for relative vertical movement, the combination of, a member between said journal boxes and including oppositely directed guideways for supporting slideable brake beams, pivot means carried by said side frame and carrying said member, pivot means carried by said side frame and spaced from said first named pivot means, said last named pivot means being movably connected to said journal boxes, and means joining related pivot means.

2. In a railway car truck wherein a side frame

and journal boxes are arranged for relative vertical movement, the combination of, a member terminating in oppositely disposed guideways for supporting brake beams, spaced means pivotally connecting said member to said side frame, spaced means pivotally connected to said side frame and associated with said journal boxes, and means pivotally connecting related spaced means.

3. In a railway car truck wherein a side frame and journal boxes are arranged for relative vertical movement, the combination of, a member between said journal boxes and comprising oppositely directed guideways for housing associated ends of slideable brake beams, lever means carried by said side frame and carrying said member, pivot means carried by said side frame and spaced from said lever means, said pivot means being connected to said journal boxes, and means connecting said lever and pivot means.

4. In a railway car truck wherein a side frame and journal boxes are arranged for relative vertical movement, the combination of, a member between said journal boxes and comprising oppositely directed guideways for accommodating associated ends of slideable brake beams, spaced lever means pivotally secured to said side frame and carrying said member, spaced pivot means carried by said side frame and spaced toward an end of said side frame from said lever means, said pivot means being connected to said journal boxes, and means pivotally connecting said lever and pivot means.

5. In a railway car truck wherein a side frame and journal boxes are arranged for relative vertical movement, the combination of, a member between said journal boxes and comprising oppositely directed guideways arranged to support ends of associated brake beams, spaced lever means pivotally secured to said side frame and carrying said member, spaced pivot means carried by said side frame and spaced toward an end of said side frame from said lever means, said pivot means being connected to said journal boxes, and means pivotally connecting said lever and pivot means; all of said lever and pivot means having arms of substantially equal effective lengths.

6. In a railway car truck wherein a side frame and journal boxes are arranged for relative vertical movement, the combination of, a member between said journal boxes and comprising oppositely directed guideways for carrying associated ends of related brake beams, spaced lever means carrying said member, rotatable means spaced from said lever means, said lever and rotatable means being pivoted to said side frame intermediate their ends, and means joining said lever and rotatable means; said rotatable means being movably connected to said journal boxes.

7. In a railway car truck wherein a side frame and journal boxes are arranged for relative vertical movement, the combination of, a member positioned inwardly of said truck from said side frame and comprising oppositely directed guideways for carrying and directing ends of related brake beams, spaced lever means extending through said side frame and supporting said member, rotatable means spaced from said lever means; each lever and rotatable means being pivoted to said side frame intermediate its ends, and means outwardly of said side frame joining said lever and rotatable means; said rotatable means having portions thereof underlying said journal boxes.

8. In a railway car truck wherein a side frame and journal boxes are arranged for relative ver-

tical movement, the combination of, a member positioned inwardly of said truck from said side frame and comprising a pair of guideways for the support of brake beams, spaced lever means having portions thereof positioned inwardly of said side frame and connected to said member adjacent extremities thereof, portions of said lever means being positioned outward of said side frame, rotatable means having portions positioned outwardly of said side frame and joined to corresponding portions of said lever means, and said rotatable means having portions underlying said journal boxes; said lever and rotatable means being pivotally secured to said side frame.

9. In a railway car truck wherein a side frame and journal boxes are arranged for relative vertical movement, the combination of, a member disposed inwardly of said truck from said side frame and having, adjacent extremities thereof, guideways for the support of brake beams, spaced lever means extending through and pivotally secured to said side frame, portions of said lever means being disposed over and connected to said member, other portions of said lever means being disposed outwardly of said side frame, means carried by said side frame spaced from said lever means, and means outwardly of said side frame joining said other portions of said lever means and first named means; said first named means being slidably connected to said journal boxes.

10. In a railway car truck wherein a side frame and journal boxes are arranged for relative vertical movement, the combination of, a member disposed inwardly of said truck from said side frame and having, adjacent extremities thereof, guideways for the support of brake beams, lugs upstanding from said member adjacent said guideways, a lever adjacent each end of said member and having an intermediate portion pivotally secured to said side frame, a crank spaced from each lever and carried by said side frame, a connecting rod extending between substantially equal arms of a related lever and crank, each lever having means joined to one of said lugs, and each crank having means joined to one of said journal boxes; said lever and crank means being of substantially equal length.

11. In a railway car truck wherein a side frame and journal boxes are arranged for relative vertical movement, the combination of, a member disposed inwardly of said truck from said side frame and having an intermediate tie terminating in guideways for the support of brake beams, lugs upstanding from said member adjacent said guideways, a lever adjacent each end of said member and having an intermediate portion extending through and pivotally secured to said side frame, a crank spaced from each lever and carried by said side frame, a connecting rod outwardly of said truck extending between substantially equal arms of a related lever and crank, each lever having means movably joined to one of said lugs, and each crank having means movably joined to one of said journal boxes; said lever and crank means being of substantially equal length.

12. In a railway car truck wherein a side frame and journal boxes are arranged for relative vertical movement, the combination of, a member disposed inwardly of said truck from said side frame and having an intermediate tie terminating in brake beam supports, upstanding lugs positioned adjacent extremities of said member, a lever adjacent each end of said member and

having an intermediate portion pivotally secured to said side frame, a crank spaced from each lever and carried by said side frame, a connecting rod outwardly of said truck extending between equal arms of a related lever and crank, each lever having means positioned inwardly of said truck and joined to one of said lugs, and each crank having means joined to one of said journal boxes centrally thereof; said lever and crank means being of equal effective lengths.

13. In an integral brake beam support arranged for movement relative to a side frame, the combination of, an intermediate tie, end portions above and joined to said intermediate tie and defining guideways, said guideways being disposed at an acute angle relative to said intermediate tie, and supporting means upstanding from said end portions.

14. In an integral brake beam support arranged for movement relative to a side frame, the combination of, a lower intermediate tie terminating at both ends thereof in raised end portions, said end portions comprising guideways extending at an acute angle to said lower intermediate tie, and spaced means upstanding from said end portions for carrying said brake beam support.

15. In a railway car truck wherein a side frame and journal box are arranged for relative vertical movement, the combination of, a brake beam extending transversely of said truck, a member arranged to be maintained substantially stationary in a vertical direction relative to said journal box, said member supporting said brake beam so that the latter will throughout its entire range of movement toward and away from said journal box be directed along a straight path fixed with relation to said journal box, and means for supporting said member; said means comprising means pivotally mounted on said side frame and connecting said member to said side frame, means pivotally mounted on said side frame and slidably associated with said journal box, said last named means arranged to be moved about its pivot by said journal box, and means pivotally connecting all of said pivotally mounted means.

16. In a railway car truck wherein a side frame and journal box are arranged for relative vertical movement, the combination of, a brake beam extending transversely of said truck, a member positioned inwardly of said truck from said side frame, said member being arranged to remain substantially vertically stationary relative to said journal box and to be moved relative to said side frame for the support of said brake beam, means for supporting said member, said means comprising lever means pivotally mounted on said side frame and having an arm thereof positioned inwardly of said truck from said side frame, said arm being connected to said member for the support thereof, and rotatable means pivotally mounted on said side frame in spaced relation to said lever means; said rotatable means having a portion thereof reacting against said journal box to be in sliding contact therewith and another portion thereof pivotally connected to said lever means.

17. In a railway car truck wherein a side frame and journal box are arranged for relative vertical movement, the combination of, a brake beam extending transversely of said truck, a member positioned inwardly of said truck from said side frame and arranged to be maintained substantially stationary in a vertical direction relative to said journal box, said member sup-

porting said brake beam so that the latter will throughout its entire range of movement toward and away from said journal box be directed along a straight path vertically fixed with relation to said journal box, and a lever mechanism having a part thereof disposed inwardly of said truck and pivotally connected to said member for the sole support thereof; said lever mechanism being pivotally mounted on said side frame and having another portion thereof bear against said journal box to be in sliding contact therewith.

DONALD S. BARROWS.
